UNITED STATES PATENT OFFICE.

ALFRED H. DAVIES, OF CLEVELAND, OHIO, ASSIGNOR, BY MESNE ASSIGNMENTS, TO THE SIXTH CITY IRON COMPANY, OF CLEVELAND, OHIO, A CORPORATION OF OHIO.

SAD-IRON.

1,098,886.

Specification of Letters Patent.

Patented June 2, 1914.

Application filed February 19, 1912. Serial No. 678,539.

To all whom it may concern:

Be it known that I, ALFRED H. DAVIES, residing at Cleveland, in the county of Cuyahoga and State of Ohio, have invented new 5 and useful Improvements in Sad-Irons, of which the following is a specification.

My invention relates to that class of sad irons which are heated by means of gas conducted to the iron proper through a suitable 10 flexible tube and also to sad irons wherein gasolene is employed for the purpose of heating the sad iron.

The objects of the present invention are, first, to provide means whereby the action of 15 the burner may be seen without removing any of the detachable parts of the sad iron proper.

Another object is to provide means for attaching and holding sheets of transparent 20 or translucent material such as mica.

These objects together with other objects readily apparent to those skilled in the art, I attain by the construction illustrated in the accompanying drawings, although my invention 25 may be embodied in other forms, the construction illustrated being chosen by way of example.

In the accompanying drawing: Figure 1 is a side elevation. Fig. 2 is a longitudinal 30 section on line 2—2, Fig. 1. Fig. 3 is a detached view of one of the skeletons designed to hold the sheets of mica or other transparent or translucent material.

Throughout the several views similar reference numerals indicate similar parts.

In the accompanying drawing, 1 represents the hollow iron body preferably of the form shown in the drawings and constituted in the usual manner, except whereby the 40 transparent or translucent sheets are properly connected. The sides of the hollow body 1 are provided with openings which openings are preferably formed of such a size that practically the entire side walls of the hollow body 1 will be cut away so that 45 the entire length of the burner 2 will be exposed to view through the transparent or translucent sheets. At the boundaries of the openings, flanges 3 are formed and about 50 midway between the front and rear ends of the hollow body 1 are located the integral

bars 4 against which integral bars 4 and the flanges 3 the transparent or translucent sheets 5 are placed and against the inner surfaces of the sheets 5 at their ends or sides 55 are placed the skeleton holders 6, which are provided with the central vertical bar 7, which is located so that it will come opposite the bar 4 when placed in proper position; and when placed in proper position as 60 illustrated in Fig. 2 the sheets of mica or like material will be clamped between the bars 4 and 7 and held in such clamped position by means of suitable screws 8.

It will be understood that the skeleton 6 65 should be curved as illustrated in the drawings so that it will conform with the curvature of the hollow sad iron 1, for the purpose of properly binding the sheets designed to be clamped and held in position. In gas 70 or gasolene heated sad irons it is of importance to know at all times as to whether or not the burner is working properly and by providing the mica sheets or other transparent or translucent material it is easy to 75 determine as to whether or not the burner is performing its functions and at the same time the flame can be easily regulated without removing the cover or other detachable parts whereby the sad iron proper is brought 80 to the desired degree of heat thereby preventing any overheating or underheating of the sad iron proper.

In the drawings I have shown conventionally a gas burner, but it will be understood 85 that other heating devices may be employed without departing from the nature of my invention.

Having fully described my invention what I claim as new and desire to secure by Letters Patent, is—

In a sad iron of the class described, the combination of a hollow body, the front or forward portion thereof consisting of a curved portion, a burner located within the 95 hollow body, the side walls of the hollow body provided with openings, an integral bar located between the end of the openings in the body, skeletons adapted to be seated against the inner faces of the hollow body 100 adjacent the openings, said openings formed of a length to correspond with the length of

the body, transparent sheets located in the openings of the body and the skeletons located against said transparent sheets, and means for connecting the skeletons to the hollow body, substantially as and for the purpose specified.

In testimony that I claim the above, I

have hereunto subscribed my name in the presence of two witnesses.

ALFRED H. DAVIES.
